FURNACE DOOR

Jesse E. Sticker, Jr., Steubenville, Ohio, assignor
of one-half to John L. Tatman, Steubenville,
Ohio

Application October 17, 1945, Serial No. 622,847

1. Claim. (Cl. 122—498)

1. The invention relates to doors for furnaces, and more particularly to a water cooled door especially adapted for use upon open hearth furnaces, melting furnaces and the like, where the inner surface of the door is exposed to extremely high temperatures.

It is common practice to provide water cooled doors for open hearth furnaces and similar furnaces, said doors comprising a shell forming a water jacket over the outer side of the door with inturned marginal rails providing a pocket upon the inner side of the door, which is filled with a suitable refractory such as fire clay, brick or a refractory cement or plastic providing a refractory inner surface for the door which is exposed to the extreme heat of the furnace.

In actual use this refractory lining is quickly burned out, burning away first at the central portion of the door while the marginal portions of the refractory lining adjacent to the water cooled marginal rails of the door remain substantially intact.

The average life of such a refractory lining in open hearth doors is about twenty heats, after which the door must be removed from the furnace, the old burned out refractory lining removed and the door relined with suitable refractory material before it is replaced upon the furnace.

This requires considerable labor as well as refractory material to reline the doors and keep them in condition for use, adding considerably to the expense of maintaining the furnace in working condition.

The object of the present invention is to provide a water cooled door for use on open hearth furnaces and the like, so constructed that the life of the refractory lining will be many times the life of the lining of the conventional furnace door.

Another object is to provide a furnace door comprising a shell forming a water jacket on the exterior side of the door and having water cooled, inwardly disposed, marginal rails, and one or more water cooled rails communicating with the water jacket and located upon the inner side of the door so as to divide the same into separate panels or pockets which are adapted to be filled with refractory material, with means for circulating cooling water through the water jacket and through all of said rails.

A further object is to provide a door of this character in which all of said water cooled rails are of less thickness toward the outer side of the door and are of greater thickness at a point toward the inner side of the door, so as to provide

substantially dove tail pockets to receive and retain the refractory lining material.

The above objects, together with others which will be apparent from the drawing and following description, or which may be later referred to, may be attained by constructing the improved furnace door in the manner illustrated in the accompanying drawing, in which:

Figure 1 is an elevation of the inner side of an open hearth furnace door constructed in accordance with the invention;

Fig. 2 a horizontal sectional view taken as on the line 2—2, Fig. 1;

Fig. 3 a vertical sectional view taken as on the line 3—3, Fig. 1; and,

Fig. 4 a fragmentary section taken as on the line 4—4, Fig. 1.

The door includes a hollow metal shell formed of the spaced outer and inner walls 10 and 11 respectively, which may be steel plates connected in spaced relation as by the pipe stays or spacers 12 having their opposite ends located within suitable openings 13 within the walls 10 and 11 and attached thereto as by welding, thus providing a water jacket or chamber over the outer side of the door as indicated at 14.

The door is provided around its marginal edges with the inwardly disposed, water cooled rails indicated generally at 15, and communicating with the water jacket 14, so that water circulated therethrough from the inlet 16 to the outlet 17 will also be circulated through said marginal rails. The inner side walls 18 of the marginal rails 15 are preferably inclined as shown in the drawing for a purpose to be later explained.

With the exception of the inclined inner walls 18 of the marginal rails, the construction thus far described is substantially the conventional form of open hearth furnace door, the marginal water cooled rails forming a pocket upon the inner side of the door which is filled with any suitable refractory material exposed to the heat of the furnace.

This refractory lining rapidly deteriorates under the high temperatures to which it is subjected, burning away first at the central portion of the door, while the marginal portions of the refractory lining adjacent to the water cooled rails 15 remain substantially intact.

The present invention contemplates a construction which prevents this rapid burning away of the refractory lining and lengthens the life of the same to many times the life of the refractory lining in the conventional door construction.

This may be accomplished by providing one or

more water cooled rails at intermediate points upon the inner side of the door and communicating with the water jacket so that cooling water is circulated therethrough, thus dividing the inner side of the door into separate pockets each of which may be filled with refractory material.

Although only a single intermediate water cooled rail is shown in the drawing, and this in vertical position, it is pointed out that one or any desired number of intermediate water cooled rails may be provided and may be located either vertically, horizontally or diagonally as conditions may require.

In the form of the invention illustrated in the drawing, a single hollow, water cooled rail 19 is provided through the vertical center of the inner side of the door, extending from the upper marginal rail to the enlarged chamber 20 communicating with the lower end of the vertical rail 19 and with the lower marginal rail of the door, and formed by the arched plate 21 which surrounds and is spaced from the pipe stay or spacer 22, having its ends located within suitable openings in the back wall 10 and in the front wall 23 of the rail 19. The pipe 22 thus forms a peep hole through which the interior of the furnace is visible so that the condition of the metal bath may be observed therethrough.

The intermediate rail 19 communicates with the water jacket 14 through the slots 24 and the straight portion of this rail communicates with the enlarged chamber 20 through the opening 25. The upper end of the rail 19 communicates with the upper marginal rail 15 through the opening 26 and the lower end of the enlarged chamber 20 communicates with the lower marginal rail 15 through the opening 27.

With this construction the inner side of the door is divided into two similar pockets which may be filled with suitable refractory material such as fire clay, KN plastic refractory cement, brick or other suitable refractory as indicated at 28.

These pockets being of dove tail form, will tend to better retain the refractory lining therein and as the refractory sections 17 are of considerably less width than in the conventional door, it has been found in actual use that the refractory lining does not burn out as quickly as in the conventional door but lasts many times the life of the refractory lining in the conventional door.

After considerable use of the improved furnace doors in a steel plant, it has been found that where the conventional door had to be relined after an average of twenty heats, doors constructed as disclosed herein will retain the lining in condition for use for an overall average of between one hundred and fifty and one hundred and seventy-five heats and in some in-

stances a door made in this manner has been used for considerably over two hundred heats before it was necessary to reline the same.

If desired, pipe sockets 29 may be located in the lower corners of the water jacket 14 and normally closed by plugs 30 which may be removed for drainage purposes, if desired.

It should be understood that although the rails are described as water cooled, any type of cooling medium may be used. Furthermore, while these rails are illustrated and described as preferably of substantially dove-tail shape, it should be understood that the rails may be of any cross sectional shape, such for instance as pipe either round or flattened, or other cross sectional shape which will form a suitable conductor for the cooling mechanism.

I claim:

10 A furnace door comprising a hollow metal shell forming a water jacket over the entire outer side of the door, inwardly disposed, hollow, water cooled rails at the marginal edges of the door and communicating with said water jacket, intermediate, inwardly disposed, hollow water cooled rail means extending to the inner side of the door and communicating with said water jacket and dividing the inner side of the door into separate pockets, refractory material filling said pockets, a transversely disposed tubular member located through the door from the outer side to the inner side thereof and providing an opening entirely through the door, and a water jacket surrounding said tubular member and communicating with the intermediate rail means and with one of said marginal rails whereby said opening is water cooled throughout its entire length.
